EPIPHANE P. SIMARD, OF WALTHAM, MASSACHUSETTS.

RAIL-JOINT.

1,129,746.

Specification of Letters Patent. Patented Feb. 23, 1915.

Application filed August 6, 1914. Serial No. 855,527.

To all whom it may concern:

Be it known that I, EPIPHANE P. SIMARD, a citizen of the United States, residing at Waltham, in the county of Middlesex and State of Massachusetts, have invented certain new and useful Improvements in Rail-Joints, of which the following is a specification.

My invention relates to improvements in welded joints for rails. Its purpose is to provide a joint of great firmness and strength and one which has great electrical conductivity.

A rail joint of my construction is so perfect and rigid that little if any depressions will be made near the ends of the rails and they will not become battered as is the case with some joints.

In making a rail joint of my construction, I dispense with the use of bolts, rivets or other similar fastening devices which are frequently used and I find it unnecessary to use rail bonds or supplementary wire between the rails to make a more perfect conductor. As the use of bolts, rivets or similar devices or of rail bonds necessitates perforating the rail ends and the connecting plate, and as I dispense with their use, the rail ends and the connecting plates are thereby stronger and less likely to break or wear out.

I use, preferably on both sides of the abutting rail ends to be joined, fish plates which overlap the junction of the rails and extend a sufficient distance each side of the point of contact of the abutting rail ends to give the necessary strength. These fish plates are so made that they fit snugly against the web of the rail and are so made at the top that they fit snugly under the ball and at the bottom so that they fit snugly above the base of the rail. They fit closely at all points of contact and as they extend from the base to the ball of the rail, they help to support and stiffen the ball at the part, that is to say near the end of the rail, where it is subjected to the most severe wear and pounding. In my preferred construction, I use a fish plate of which the edges which adjoin the rail web, ball and base are grooved, toothed or both whereby the parts may be better welded and better electrical contact is secured. I also prefer to use a vertical reinforcing rib on the outside of

the fish plate extending downward from 55 the top flange at a point opposite the adjoining ends of the rail.

In my construction, I use rails with square cut ends which abut against each other and come as closely together as possible. 60

In the drawings, Figure 1 is a side elevation of a rail joint embodying my invention with my preferred form of fish plate. Fig. 2 is a section thereof on line X—Y. Fig. 3 is a side elevation with parts broken 65 away showing another form of fish plate. Fig. 4 is a section thereof seen from the right of line M, N. Fig. 5 is a side elevation of another form of fish plate. Fig. 6 is a perspective view partly in section of 70 another form of fish plates in place on a rail of which the ball has been removed to show the top of the fish plates. All the above are shown with the fish plates in position but not welded or brazed. Fig. 7 is 75 a side elevation showing another form of fish plate in place and welded. Fig. 8 is a section on line S—T.

In the preferred form shown in Figs. 1 and 2, A and B are two adjoining rails 80 the ends of which are to be joined. These ends are brought closely together and the fish plates C and D are fitted in on each side of the joint. These fish plates are of substantially the same construction except that as the bottom of the flange 10 of the rail is a greater distance from the base 11 than is the flange 12, the fish plates C and D are of different heights and are shaped respectively to fit the curve 90 of flange 10 or the curve of flange 12 where they adjoin and run into the respective surfaces of web 13. Each fish plate as C at the top is preferably formed with an outwardly extending flange 20 along the upper 95 outer edge of which is a longitudinal recess or groove 21. At the bottom, each plate as C has a similar longitudinal recess or groove 23. These recesses serve to receive the welding material and to hold it in place 100 both before it has cooled and afterward thereby making a stronger joint and one which gives better electrical conduction. The top of each fish plate as C of this preferred construction is shorter than the bottom whereby the sides 24 and 25 extend outward forming a trapezoid with equal sides, 105 I prefer to form each side with a plurality

of recesses where it adjoins the web of a rail which preferably take the form of notches or teeth 26 or 27. As shown in Fig. 1, the upper surface 28 of each tooth 5 may be flat and the side thereof beveled to an edge as 29. I prefer also to have cast integral with each fish plate as C a vertical rib as 30 which extends downward in the form of a half cone from flange 20 toward the bottom of the plate. This form of fish 10 plate is welded to the rail along the recesses 21, 23, 26 and 27 and as it has a long line of welding in proportion to its size, it has great conductivity. By the use of toothed 15 recesses 26 and 27, if a crack should start between the welding and the metal, it will not be continuous as it might be with a straight line of welding.

In the construction shown in Figs. 3 and 20 4, I use fish plates as E, F, each of which fits snugly against the web of the rails G, H and also against the under part of the ball and the top of the base. In this construction, each fish plate as F has at the 25 top outer edge a recess or groove 32, at the bottom outer edge a recess or groove 33 and at each end a recess 34 and 35. It also has a reinforcing rib 36. These plates are welded into position by introducing the welding 30 material into the recess 32, 33, 34 and 35 which adjoin portions of the rail as indicated. In Fig. 5, I show a form of fish plate K which has recesses or grooves only at the top 40 and at the bottom 41. This 35 may be welded in these grooves and also along the ends 42 and 43. It has a reinforcing rib 44.

In Fig. 6, I show a construction which I may use, wherein the fish plate L has at 40 each end, toothed recesses 50 and 51 similar to teeth 26 and 27 shown in Figs. 1 and 2 and has also at the top a plurality of toothed recesses 53 and at the bottom, a plurality of toothed recesses 52. The bottom edge 45 is longer than the top and it has a reinforcing rib 54 as shown.

In Figs. 7 and 8, I show another form of fish plate O, P, wherein each plate as O has a top longitudinal recess or groove 60, 50 a bottom longitudinal recess or groove 61, while the ends 62 and 63 are not grooved and there is no reinforcing rib. In this 55 case as in the construction shown in Fig. 5, the welding material is introduced into the grooves 60 and 61 at the top and bottom and into the angle formed at the junction point between the ends 62 and 63 and the rails Q, R.

The sectional views show some of the different types of rails to which my fish plates 60 can be applied but there are other types with any of which they can be used, if properly shaped, on the adjoining surfaces.

I prefer to use a flange which extends 65 outwardly from the top of each of my fish

plates so that as the ball of the rail wears down from the top, it will be reinforced and supported by said flange.

In the welding process, that part of the rail and of the fish plate which adjoins the welding material 70 is more or less softened 70 and melted and merges with the welding material so that it is difficult, if not impossible, to tell where one leaves off and the other begins. My recesses or grooves 75 assist in this merging and also help to direct the welding material to the proper place without waste.

It is clear that were there any object in so doing a single fish plate of my construction might be used on one side of the rail ends and a fish plate of another construction upon the other side.

I claim:

1. A rail joint comprising rails whose 85 ends abut, and a pair of fish plates each of which fits on an opposite side of the webs of the rails and overlaps the ends thereof each having a top flange which fits under the ball of the rail and being shaped at 90 the bottom to fit the base thereof, each fish plate having recesses at its edges which adjoin the rails and being welded to the rails along said recesses.

2. A rail joint comprising abutting rail 95 ends and a fish plate at the side of said ends, said fish plate being fitted snugly to the web of the rails and to the ball and base thereof and having along its top and bottom edges adjoining the ball and base of 100 the rails, longitudinal grooves and at its ends having toothed recesses adjoining the webs of the rails said plate being welded to the rails along said grooves and toothed recesses as described.

3. A rail joint comprising rails whose 105 ends abut, and a pair of fish plates each of which fits on the opposite side of the webs of the rails and overlaps the ends thereof each having a top flange which fits under the ball of the rail and a reinforcing rib which extends downward therefrom and said fish plates being shaped at the bottom to fit the base thereof, each fish plate having recesses at its edges which adjoin the 110 rails and being welded to the rails along said recesses.

4. A rail joint comprising abutting rail ends, and a fish plate at the side of said ends, said fish plate being fitted snugly to 120 the web of the rails and to the ball and base thereof and having along its top and bottom edges which adjoin the ball and base of the rails toothed recesses and having at its ends toothed recesses which adjoin 125 the webs of the rails said plate being welded to the rails along said toothed recesses as described.

5. A rail joint comprising abutting rail ends and a fish plate at each side of said 130

ends each of said fish plates being fitted snugly to the web of the rails and having a top flange which fits under the ball of the rail and a reinforcing rib which extends 5 downward therefrom, said fish plate being shaped at the bottom to fit the base of said rails and having along its top and bottom edges and along each end toothed recesses which adjoin the rails said fish plate being

welded to the rails along said toothed recesses as described.

In testimony whereof I hereto affix my signature in presence of two witnesses.

EPIPHANE P. SIMARD.
